UNITED STATES PATENT OFFICE.

JOHN L. WOOD, OF DALLAS, TEXAS.

RULING-BLOTTER.

No. 799,818.

Specification of Letters Patent.

Patented Sept. 19, 1905.

Application filed September 7, 1904. Serial No. 223,598.

To all whom it may concern:

Be it known that I, JOHN L. WOOD, a citizen of the United States, and a resident of Dallas, in the county of Dallas and State of Texas, 5 have invented new and useful Improvements in Ruling-Blotters, of which the following is a specification.

My invention relates to a ruling-blotter.

It has for its object to provide a blotting-10 pad having on one face a measure, a calendar, and spaces for advertising matter, and a straight-edge secured along its edge to afford ready and convenient means for ruling straight lines with a pencil or pen.

15 It has for a further object to provide a blotter of the character set forth combining advantages in point of simplicity, inexpensiveness, and general utility.

In the drawings, Figure 1 is a plan view; 20 Fig. 2, an enlarged end view; Fig. 3, an enlarged fragmentary detail view thereof; Fig. 4, an enlarged end view of a modified form. Fig. 5 is an enlarged fragmentary detail view of the modified form.

25 Corresponding parts in all the figures are denoted by the same reference characters.

Referring to the drawings, 1 designates a blotting-pad of any desired dimensions, on the face 2 of which along the edge are graduations forming a measure 3. Below said measure is a calendar 4, and below the calendar are a number of spaces 5 to have advertising matter printed thereon.

30 A straight-edge 6 is provided along the edge of the blotting-pad having the graduations and consists of a round strip 7 of metal or other suitable material secured thereto by a binding-strip 8 of oiled silk, oiled paper, or other suitable material, so that it will project 35 above the face 2 of the blotting-pad and come practically flush with the other face thereof, said binding-strip 8 inclosing the strip 7 and having its edges secured to the opposite faces of the blotting-pad by glue or cement.

40 Referring to the modification, this form of my invention only differs from that shown by the other views in that the straight-edge consists of an angular strip 10 of metal or other suitable material secured to the blotting-pad 45 by a strip 11 of oiled silk, oiled paper, or other suitable material, so that it will project above the face 2 of the blotting-pad and come

practically flush with the other face, said binding-strip inclosing the strip 10 and having its edges secured together and secured to 55 one face of the blotting-pad by glue or cement.

It will be understood that the strips 7 and 8 strengthen the blotting-pad, and thereby prolong its life, and that by reason of these strips projecting beyond the surface 2 thereof 60 the ink is prevented from disfiguring the calendar, measure, and advertising matter thereon and from spreading over the surface of the book or paper being ruled off.

Having thus described my invention, I claim 65 and desire to secure by Letters Patent—

1. A ruling-blotter comprising the pad, a strip of relatively hard material forming a straight-edge extending along the edge of the pad, and means connected with said strip and 70 with the pad and adhesively securing said members together.

2. A ruling-blotter comprising the pad, a strip of relatively hard material forming a straight-edge extending along the edge of the 75 pad, a binding of flexible material connecting said edge strip to the pad, and means for adhesively securing said flexible strip in its binding position.

3. A ruling-blotter comprising the pad, a 80 strip of relatively hard material forming a straight-edge extending along the edge of the pad, and a binding-strip of flexible material surrounding said edge strip and having its ends or edges projecting therefrom and secured to the pad.

4. A ruling-blotter comprising the pad, a strip of relatively hard material forming a straight-edge extending along the edge of the 90 pad, a binding-strip of flexible material surrounding said edge strip and having its ends or edges projecting therefrom, and adhesive means for connecting said projecting ends or edges to the pad.

5. A ruling-blotter comprising the pad, a 95 strip of relatively hard material forming a straight-edge extending along the edge of the pad, a binding-strip of flexible material surrounding said edge strip and having its ends or edges projecting therefrom, and means for 100 adhesively connecting both of said projecting ends or edges to the pad.

6. A ruling-blotter comprising the pad, a strip of relatively hard material forming a

straight-edge extending along the edge of the pad, and a binding-strip surrounding and inclosing said edge strip and secured to the pad.

7. A ruling-blottor comprising the pad, a
5 strip of relatively hard material forming a
straight-edge extending along the edge of the
pad, said edge strip projecting above one face
of the pad and being practically flush with
the other face of the pad, and a relatively
10 thin binding-strip connecting the edge strip

and pad together, whereby the edge strip and
binding means involve no material projec-
tion except at one face of the pad.

In testimony whereof I have signed my name
in the presence of the subscribing witnesses. 15

JOHN L. WOOD.
